UNITED STATES PATENT OFFICE.

HARLEY S. HEATH AND MILLARD L. HEATH, OF KENTON, OHIO.

CIRCUIT-BREAKING MEANS FOR MOTOR-VEHICLES.

1,085,608.

Specification of Letters Patent.

Patented Feb. 3, 1914.

Application filed October 26, 1911. Serial No. 656,757.

To all whom it may concern:

Be it known that we, HARLEY S. HEATH and MILLARD L. HEATH, citizens of the United States, residing at Kenton, in the county of Hardin and State of Ohio, have invented certain new and useful Improvements in Circuit-Breaking Means for Motor-Vehicles, of which the following is a specification.

10 This invention relates to a device for automatically shutting off an engine or motor of the explosive or internal combustion type when same is mounted on a motorcycle or similar machine, when the latter is upset or 15 is tilted at an angle so great as to be likely to result in the overturning of the machine.

The especial object of the improvements of our invention is to provide automatic shut off or circuit breaking means whereby the 20 electric circuit connected with the spark plug or any similar spark producing means, is broken when the cycle or machine on which the motor is mounted, is tilted to a dangerous angle in its operation, or is over-turned.

30 A further object of said invention is to provide a device of the character described that will be cheap to manufacture, add but little to the weight of the motor vehicle, and 35 that will operate with certainty under the conditions predetermined for the device.

In the accompanying drawing, we have shown an adaptation of our invention especially applicable to motorcycles, but it will 35 be understood that the essential features illustrated may be modified as to mechanical details without departing from the invention upon which we desire a patent, and that it may be applied to other styles of machines 40 than motorcycles.

45 While we have not shown our invention as applied to a motorcycle, it will be understood that it may be clamped or secured to such portion of the frame of the vehicle as will be most convenient and which will surely operate in case the machine is tilted at an angle to which the automatic controlling device is adapted.

50 In the accompanying drawing:—Figure 1 shows partly in elevation and partly in section a circuit breaking or controlling device

embodying our invention; Fig. 2 is a bottom plan view of the device; Fig. 3 is a detail on an enlarged scale of the frictional control which forms a feature of the device 55 as a whole, and Fig. 4 is a sectional detail of the terminal connections for the circuit wires.

Referring to the details of the drawing, 4 represents a box or casing preferably made 60 of thin sheet metal in the trunco-conical form illustrated. The bottom wall of the casing is curved and throughout the greater part of its length is provided with a longitudinal slot 4^a. Secured to the outer face of 65 the bottom wall at a point adjacent one end of the slot, is an angular stop 4^b and on one side of the slot near its ends, are two lugs 4^c. Projecting at right angles from the rear wall of the casing is a bracket 4^d in which 70 are suitable bolt holes 4^e to receive the bolts, 4^f, by which the device may be attached to a motor cycle frame in any desired manner.

5 is a plate of insulating material rigidly secured within the casing at the rear wall 75 thereof. To one side of this plate is attached, a contact plate 6 having contact surfaces of different radii, 6^a, 6^b, 6^c. This plate is in circuit with binding posts 7^c, 7^d, which project through the rear wall of the casing and 80 through openings provided therefor in the plate 5. These posts it will be understood, are connected by suitable wires with the circuit in which the spark plug of the motor is placed.

85 7 represents the pendulum rod which as shown, is made of a rod of round brass and is pivoted at its upper end on the binding post 7^c. To the lower end of the rod 7 is fixed a cylindrical pendulum 7^a of suitable 90 material, and extending through the rod at a point just above the pendulum, is an opening 7^b to receive the guide rod 10.

95 8 represents a pair of opposed contact bars which are connected with the pendulum rod 7 by a boss 9 in which a hole 9^b is formed to receive the rod, and a thumb screw 9^a passes through the boss and has its inner end impinging on the rod so as to secure the bars 8 in position on said rod. One end 100 of the bars 8 is flexibly connected by a link 8^c and the other ends are connected by an

expansion spring 8^b, the tension of which is exerted to hold the bars apart and thus provide a yielding support for the roller 8^d which is mounted in the roller box 8^c, the latter being secured to the outer face of the bars 8.

10 represents a guide-rod bent in the arc of a circle and adjustably connected by screws 10^a secured in its ends and fitting 10 in slots 11^a in the free ends of the radial bars 11 which are secured at the inner ends to the plate 4. The rod 10 has a close sliding fit with the pendulum rod 7 at the slot 7^b.

15 12 represents an adjustable stop having an extension 12^a which projects through the slot 4^a in the casing 4, and an oppositely arranged extension 12^b which projects vertically into the casing. This stop is held in 20 adjusted position in the casing between the two stops 4^c by a small spring 12^c, one end of which is secured to the stop and the other end frictionally engages the under face of the bottom wall of the casing as clearly 25 shown in Fig. 2. As shown in Figs. 1 and 2, the stop 12 is arranged at the right hand end of the casing by the spring 12^c being pushed to the outer side of the lug 4^c at that end of the casing. In this position, the stop does 30 not interfere with the swinging of the pendulum 7^a. If it be desired to throw the pendulum out of engagement so as to make it inoperative, the stop 12 is pushed to the opposite side of the casing or to the position 35 indicated by dotted lines in Fig. 1, and when in such position the spring 12^c will have passed over the lug 4^c at that side of the casing and the stop will be held against the angular stop 4^b and the pendulum will be held 40 at the corresponding end of the casing. It will be understood that so long as the roller 8^d is in contact with any portion of the contact plate the circuit in which said parts are connected is closed and that as soon as 45 said roller leaves said plate 6 and engages the insulating plate 5, the circuit will be open.

The operation of the above described appliance will be apparent, provided it be further understood that the entire device is so 50 mounted that as the motorcycle to which it is secured inclines from one side to the other the pendulum 7^a will be correspondingly swayed. By making the contact portions of 55 the plate 6 of different radii as indicated at 6^a, 6^b, etc., it is obvious that as the radii 6^c is much shorter than the surface 6^a, the roller 8^b will leave the contact plate much more quickly than if the roller is set opposite the 60 portion 6^a. Hence, if the device is to be used by a beginner in motorcycle riding, he will adjust the bars 8 on the pendulum rod 7 so as to bring the roller 8^d opposite the portion 8^c whereupon the swinging of the

pendulum in either direction will break the 65 circuit upon a comparatively slight inclination of the motorcycle. As the operator becomes more proficient in the use of the machine and therefore is able to maintain the equilibrium of the cycle even though the 70 latter may be inclined considerably from the upright, he will move the bars 8 upward on the pendulum rod by loosening and then tightening the set screw 9^a until the contact roller reaches the portion 6^a. If the rider 75 does not need the device, or for any reason wishes to cut it out of circuit he may disconnect the wires with the binding posts or move the stop 12 to the position indicated in dotted lines in Fig. 1.

80 It will be understood that one side of the box 4 is removable or if desired, may have a door therein or other means may be provided for getting access to the adjusting screw 9^a whereby the bars 8 may be moved 85 up or down along the rod 7.

Having thus described our invention what we claim as new, is:—

1. Circuit breaking means for motor vehicles, consisting of a casing adapted to be 90 connected with the motor vehicle frame, and insulated therefrom, a contact plate secured within said casing and a member mounted in said casing to swing normally in contact with said plate, said plate and member being connected with the respective branches of an electric circuit and adapted to close 95 said circuit when in contact with each other and to open it when out of contact.

2. Circuit breaking means for motor vehicles, consisting of a casing adapted to be 100 connected with and insulated from a motor vehicle frame, a graduated contact plate fixed within said casing, and a member mounted in said casing to swing normally 105 in contact with said plate, means for adjusting the point of contact between said swinging member and said plate, said plate and member being connected with the respective branches of an electric circuit and adapted to close 110 said circuit when in contact with each other and to open it when out of contact.

3. A casing adapted to be attached to a 115 motor cycle frame and insulated therefrom, a contact plate arranged in said casing and connected with one branch of the spark plug circuit of said vehicle, a pendulum mounted in said casing adapted to swing with the lateral movements of said vehicle, connected 120 with the other branch of said circuit, and normally in contact with said plate, and means for holding said pendulum out of contact with said plate.

4. A casing adapted to be rigidly attached 125 to the frame of a motor-cycle and insulated therefrom, a plate fixed in said casing connected with one branch of the spark plug

circuit of said motor-cycle and having contact areas of different extent, a pendulum swingingly mounted in said casing and connected with the other branch of said circuit, 5 adjustable means whereby said pendulum may be in contact with the different areas of said plate, and means for holding said pendulum out of contact with said plate.

In testimony whereof we affix our signatures in the presence of two witnesses.
